UNITED STATES PATENT OFFICE

ANDREW THOMA, OF CAMBRIDGE, MASSACHUSETTS, ASSIGNOR TO NORTH AMERICAN CHEMICAL COMPANY, OF BOSTON, MASSACHUSETTS, A CORPORATION OF MASSACHUSETTS

PROCESS OF FILLING SHOES

Application filed August 4, 1927. Serial No. 210,558.

This invention pertains to the manufacture of shoes and relates more particularly to a process of filling shoe bottoms, the present application being a continuation in part 5 of my copending application Serial No. 133,506, filed September 3, 1926. My preferred process or method of filling shoe bottoms (particularly McKay shoes) is new in providing a filler piece, preferably a spreadable piece, that is capable of holding an external film of water or other liquid capable of keeping the filler piece positioned as placed by the operator until at least the sole fastening operation, immersing or wetting said 10 piece (preferably throwing a number thereof into a water container), and then placing the wetted piece in filler laying position; it is new in then placing it and securing it on the outer sole, or, if preferred, in the shoe-bottom cavity. The further preferable step of 15 thorough wetting or otherwise conditioning the filler material (in addition to or aside from the step of causing adhesion just mentioned) prior to its application is new, as further elaborated later herein and is broadly claimed in my application Serial No. 242,085, filed December 23, 1927, which in 20 part is a continuation of the present application. Also, further enumerating the broadly new features claimed and hereinafter set 25 forth in detail, my process or method is new in positioning the spreadable filler layer to its final or ultimate position by means of pressure which is solely vertical, i. e. perpendicular to the shoe bottom as distinguished from the lateral or back and forth movement heretofore (of the heated laying roll or trowel-like knife in the hand of the operator). It is new in accomplishing the final 30 positioning of the entire filler layer by a single pressure. It is new in applying the pressure for molding or spreading the filler into all parts of the cavity through or by the aid of the sole. It is new in using and employing 35 the sole leveling pressure as the filler spreading and expanding pressure. It is new in first applying a filler piece so as to occupy less than the entire area of the shoe-bottom cavity at least a portion of which filler piece is 40 dis- tensible or expandible and then expanding

said filler piece to its ultimate cavity filling position by means of said vertical pressure, preferably through the sole, and preferably by the sole leveling operation. It is new in doing the foregoing cold, i. e. at normal or 55 working temperatures as distinguished from requiring temperature treatment, either hot or cold. It is new in providing as an article of manufacture a self-sustaining or shape 60 maintaining filler piece which is expansible, placing the same in the shoe-bottom cavity between the inner sole and outer sole and then expanding it within the confines of the cavity. It is new to interpose between the inner sole and outer sole spreadable filler material in the 65 shoe-bottom cavity and then spreading it to final position for holding and in such manner as to support said two soles as a unit. It is new to cause said two soles and the filler to 70 function together as a unit. These and other features enumerated toward the end of this description are the prominent features of 75 novelty but many subordinate or lesser features will be apparent from the following description and as defined in the appended claims.

In a long series of patents, of which I cite No. 808,224, December 26, 1905, and No. 832,002, September 25, 1906, as specific examples, I have disclosed certain shoe-bottom 80 filler compounds which are generally similar in respect to the following characteristics, to wit: They are permanently sticky, 85 resilient, pliable, and compressible when cold, extremely adherent to leather, waterproof or water-repellent, capable of becoming fluid or semi-fluid when heated, non-inflammable, heat-insulating, and relatively non-shifting when confined as a filler within the cavity of 90 a shoe bottom.

As described in my prior patents, this filler material is disposed in the shoe-bottom cavity while in a plastic semi-fluid state, and is spread while still plastic by means of suitable instrumentalities, for example a broad bladed knife. In order to spread the material in this manner, it is necessary that it be semi-fluid, and in applying filler of this general character heat has always been employed 95 and considered necessary at one or another 100

stage of the filling process in order to reduce the filler to the proper degree of fluidity for spreading and then the spreading is done by a lateral or forward and back trowel-like movement over the shoe-bottom cavity.

In my copending application Serial No. 183,302, filed April 13, 1927, I describe a novel form of filler having in general the same characteristics as my prior patented filler com-
10 pounds, notably the permanent stickiness, elasticity, pliability and waterproof qualities of such compounds but embodied in a coherent self-supporting layer or sheet-like piece of a shape approximating that of the cavity in the shoe bottom and applicable to the shoe while cold, that is, at normal room temperature.

In my said copending application, as well as in my copending application Serial No. 20 192,076, filed May 17, 1927, I have enumerated certain advantages flowing from the employment of a filler of this novel form, among which I mention the elimination of the usual machine employed for heating the bulk filler, 25 with its adjunctive instrumentalities for spreading and smoothing the filler, the saving in floor space through elimination of this machine, the increased speed of the filling operation, the greater neatness of the work-
30 room, and the facility with which the filler material may be handled, shipped and stored. In my copending applications Serial No. 211,157 filed August 6, 1927, Serial No. 228,236 filed October 24, 1927, Serial No. 35 228,588 filed October 25, 1927, Serial No. 232,279 filed November 10, 1927 and Serial No. 242,085 filed December 23, 1927, other advantages are set forth.

Not only does the novel filler leaf or article, as disclosed in my aforesaid copending applications, facilitate the manufacture of a shoe in the above particulars, but it has additional advantages, among which I note its applicability to shoes of the McKay type, 45 wherein the cavity in the shoe bottom is shallow so that proper spreading and evening of the semi-fluid filler by my old process is difficult or impracticable and where, owing to the relative cheapness of such shoes, the 50 cost of the spreading operation is practically prohibitive. On the other hand, the McKay type of shoe presents certain structural characteristics making it difficult properly to fill it with other types of filler. Thus, in the 55 McKay shoe the marginal portion of the upper is disposed in folds or pleats upon the inner sole and the cavity defined by the edge of the upper varies in size and is of irregular and non-uniform outline so that solid, 60 filler pieces of felt, leather-board, or the like, rarely fit the cavity and almost never provide a smooth and uniform surface extending over the entire bottom of the shoe for contact with the inner surface of the outer 65 sole, and hence the outer sole is improperly

supported, wears unevenly, and the resulting shoe is uncomfortable to the wearer. Furthermore, the McKay type of shoe is prone to squeak due to the frictional contact of the inner sole and outer sole against each other or against the intervening dry and solid filler elements.

I have succeeded by my present invention in making it practicable to employ my old type of filler in the McKay type of shoe, but in such novel method and structure as to eliminate the difficulties and objections above explained and also the undesirable features of such shoes as just mentioned since it furnishes a smooth, complete, even and uniform support for the outer sole, renders the supporting part of the shoe comfortable to the foot supported, and incidentally interposes anti-squeak material between those parts of the inner sole and outer sole which tend to rub and squeak. In addition, my novel filler and process help to make the shoe waterproof and so firmly unite the inner sole and outer sole that they function as a unit. Thus, it is possible, if desired, to use a cheaper or thinner inner sole than usual without substantial sacrifice of strength or wearing qualities. I will hereinafter more fully describe the process by which I obtain these desirable results, having reference to the accompanying drawings for illustration of a certain desirable sequence of steps comprised in my preferred process, together with apparatus and appliances useful in performing some of said steps, it being understood that these illustrations are merely by way of example of a desirable sequence of steps and are not restrictive of the invention or conclusive of the number or order of the steps employed or of the apparatus used in performing the individual steps or the process as a whole. Moreover, while as illustrated the process is shown as applied to the filling of a McKay shoe, it is not intended, except in its more limited aspects, to restrict it to this use or environment.

In the drawings:

Fig. 13 is a transverse section, to larger scale, substantially on the line 13—13 of Fig. 12;

Fig. 14 is a section showing the outer sole in position and indicating the appearance of the filler piece after the leveling operation; and

Fig. 15 is a diagrammatic plan view showing the appearance of the bottom of a McKay shoe after leveling and with the outer sole removed.

In the practice of my present process I prefer to employ for the best and most complete 25 results a filler leaf or piece of coherent self-supporting character comprising a plastic, sticky and waterproof layer of shoe filler of the general character disclosed in any of my patents or copending applications above referred to, although in its broader aspects my present process is not necessarily confined to the employment of such a filler leaf. Preferably also the filler material is of the modified kind of my copending application Serial No. 35 211,157, filed August 6, 1927, comprising or at least containing in part an ingredient or a compound such as water alone or one of colloidal nature such as gluey or gelatinous material or materials which are changeable by 40 pressure; for instance, an emulsion of vegetable or mineral compounds, gelatin, glue, or anything of a colloidal nature that can be made to have proper fluidity to break down under pressure. In the case of a pressure release thus of water from the compound the water simply evaporates so that it results that the filler layer has been made by the pressure step stiffer or inherently more stable in position as a part of the shoe bottom. An 45 example of this is milk of magnesia which when pressed between absorbent surfaces quickly dries or, in other words, to the extent of its entering into the filler, it acts, under the leveling pressure, to stiffen the general 50 filler body and render its less shifting in tendency by reason of its resulting change in composition. In all the above the carrier is either wholly or partially separated from its original component substance by the pressure 55 under the conditions involved. When in addition to the above a comminuted absorptive body material such as chopped or ground fibers of wood, including cork, are used in the 60 filler, the aforesaid change under pressure is still more marked, because the comminuted

material, in the filler, as an article of manufacture, contains or has absorbed a modicum of water or of the colloidal compound, which (all as described at length in my application Serial No. 211,157 above) is pressed out or ejected when the laid filler is compressed by the leveling pressure, and thereupon the then compressed body material at once, to the extent that it is released under the filler's spreading action in the shoe cavity, absorbs or takes into itself certain of the other constituents, if any, of the compound and of the sticky binder, or other form of binder as the case may be, thereby stiffening the laid filler layer and giving permanency and firmness of 75 position and of support to the filler layer and to the entire shoe bottom. Meanwhile the water or other compound or ingredient as it is being ejected acts as a lubricant to facilitate the movement of the filler material to the 80 final position in the shoe bottom, and then the water evaporates, or if the filler material contains a compound which will unite with it such as starch (or any other explained in my applications Serial Nos. 183,302 and 90 211,157) it unites to form paste, acting first as a slippery agent and then as a stiffener, by evaporation or absorption. If oil or soluble oil is the compound used, its action is the same when ejected in whole or in part and it 95 is then absorbed, thereby giving increased stiffness, or enters further into the mixture as the case may be. In all these examples the filler becomes more spreadable during the pressure, and then becomes less spreadable 100 and stiffer subsequent thereto. The included water or other volatile, evaporable or absorbable compound is held inactive until the pressure or other means releases it. The filler material may be said to be composed of 105 three parts, a body material and a binder which have a tendency to unit or an attraction or affinity or intimacy, and means, such as the water, or a coating of dry starch enveloping the cork granules, or paste likewise, 110 or other, constituting a barrier tending normally to restrain said union prior to use, but as soon as the filler in said condition and in the shoe bottom is subjected to pressure the barrier is thereby at once released. The barrier ingredient then acts as a flux for the filler material, rendering the latter temporarily 115 more movable and more adherent. The ingredient which I have referred to as a barrier or dormant element encloses the cork or 120 other body granules as a coating, like a skin, especially when gelatinous or as a thick paste, and in my copending applications Serial No. 245,001 filed January 6, 1928, and Serial No. 245,002, filed January 6, 1928, I have explained further advantages and relations 125 which not only may carry out the functions already described herein but greatly promote lightness of weight in the commercial product, cheapness of manufacture, keeping qual-

5 ities (especially in the presence of dampness), etc., and certain claims herein are intended to be generic to the disclosures of all these applications, so far as this basic idea is present.

10 As shown in Figs. 1 to 3 on a considerably enlarged scale, the filler piece, in the form of a large sheet at first before cutting into the sizes or pieces required for use, comprises preferably two covers or supporting layers 11 and 14 of paper or paper-like material or textile fabric 11' and 14' or any other suitable substance adapted to form a protective skin, and an intermediate layer 15 of sticky plastic filler, so as to produce a resulting composite sheet of sufficient strength and coherence to be self-supporting, at least when cold, said supporting layers or covers 11, 14 being preferably waterproof, at least on their 15 inner surfaces next to the plastic layer 15. At least one of the outer layers is preferably of absorbent material. Preferably the finished sheets are coated or dusted on one or both sides with a substance adapted to deaden 20 or dull any stickiness that may be present, intentionally or unintentionally, to prevent their sticking when piled for cutting and also if desired to make the surfaces of the final sheet actually slippery. Thus they may 25 be dusted or coated with dry inert powder, for example a powdered mineral such as talc or soap stone which has an unctuous slippery feel or such mineral materials may be combined with organic substances, for example 30 cork dust or dry starch or the like may be used (which may become pasty under the water treatment later). This is especially desirable if one of the webs, 14 or 14' for instance, is omitted and replaced by such a 35 layer T.

40 In preparing the individual filler pieces or leaves from the sheet as above described, I may proceed as indicated in Figs. 4 and 5 by providing regions of weakness in any manner, 45 as by scoring the composite sheet on opposite sides, along lines 26 and 27, (Fig. 4), to provide a series of superposed long and narrow panels 28, each flexibly united to adjacent panels by one of the outer skins and collectively making a compact bundle. I now cut 50 through this bundle along transverse lines, which are preferably straight to minimize waste, dividing the bundle into blocks such as shown for example in Fig. 5 where the 55 block is of trapezoidal contour. This block now consists of a string of superposed sections 34, 34', etc., each of trapezoidal form, adjacent sections being flexibly united along their broader bases, as indicated at 35, and along their narrow bases, as indicated at 36. The individual sections 34 and 34' may be removed from this series by cutting, tearing or otherwise, at the regions of weakness, previously mentioned, but I prefer to remove two 60 such sections as a unit, as indicated in Fig. 8

where the sections 34 and 34' are shown as united along the line 35, thus forming the individual filler piece or leaf L. The above procedure just outlined is more fully described in my copending application Serial No. 192,076, filed May 17, 1927. As an alternative method of procedure in preparing the individual filler leaf, I may, as indicated in Fig. 6, cut through the thickness of a single sheet of the composite material, or through a series of piled up sheets, by means of a knife of zigzag form which forms a cut such as indicated at Z, Z in Fig. 6. By making a second cut which is staggered with respect to the first cut I produce a string of filler pieces or leaves L' of the same form as the piece L shown in Fig. 8, but without the transverse incision indicated at 35 in Fig. 8. These filler pieces L', of double trapezoidal form, are weakly united at their small ends 36' (which may be made still more slender and therefore weak, if found desirable) and also, if desired, the strip or string of united filler pieces may be further weakened along the lines 36' by an incision, indentation, perforations, or otherwise to facilitate their subsequent ready separation.

55 Whether the material be prepared in accordance with the procedure of Figs. 4 and 5 or that of Fig. 6, there results a long flexible string of filler pieces, as indicated in Fig. 7, adjacent pieces or leaves being united at their narrow portions, where the string may be weakened if desired as above described to facilitate their separation. Optionally, the individual filler pieces (L' or L) 60 may be separated by the manufacturer (or by the user) and packed for shipment or stored in preparation for subsequent use.

Having at hand the filler pieces as above 65 explained, I am now ready for one of the most radically novel and important features of my present invention. It has heretofore been considered necessary to fasten the filler piece solidly in place in the shoe bottom cavity 25 by some means as, for instance, by a tack, which would occasionally work up through the inner sole in the subsequent wearing of the shoe. And even when, as sometimes, a piece of pasteboard or leather-board 70 has been used by the aid of a drop or dab of glue, it has always been stuck into the shoe-bottom cavity. The cavity has been the element to receive the piece, for the obvious reason that the piece heretofore used 75 has had to be cut to fit the cavity, so that it was naturally then placed in said cavity. The operator would simply have made trouble for himself by attempting to put 80 said shaped piece on the outer sole first. On the contrary, as a radical departure in nearly all respects, I provide first the filler in the form of a died-out piece as described, which is purposely not fitted or conformed to the 85 cavity which it finally occupies, but made of 90

a shape quite different from the cavity and preferably standard for all shapes of cavities and is purposely made smaller but expandible so as later to expand to fit the cavity. Also the filler piece is so shaped and constructed that it is entirely practicable to insert it into the shoe without extraneous or independent fastening at the time of sole laying and preferably it is placed down on the outer sole instead of in the cavity. All this is a radical departure in the art of shoe making. It is new in many respects. It saves time, labor, requires less floor space and is much more direct, simple and effective. To describe the method in detail I first immerse or thoroughly wet one of my filler pieces of any of the kinds noted, preferably dumping a quantity of them into a water container. The layer or layers 11, 14 of cover material are sufficiently responsive to water, preferably hot water, at the time of use, for the purpose of this process, even though they are waterproof, at least next to the plastic inner layer (to prevent undesired absorption of the layer 15 prematurely). The sole layer now takes a wetted piece quickly from the container or wetting basin or apparatus and simply lays it in proper position down on the inner face of the outer sole 29. The outer surfaces 11 and 14 of the filler piece are capable of holding a water film on and in their external surfaces with the result that when the filler piece is thus taken from the immersing basin and quickly placed on the sole, this water film sticks the piece in place so to speak by rendering the contacting surfaces temporarily friction-holding and also by the suction action due to the presence of the water between the two perfectly flat, smooth surfaces. The water constitutes one form of temporary adhesive in this connection and for the purpose and environment of this process. The rest of the shoe (on its last as is customary) is now placed down in proper alignment on the sole and filler piece so that the shoe-bottom cavity receives or encloses properly the filler piece, as shown in bottom view in Fig. 12, where the outer sole is omitted for clearness in showing the position just explained. This is very readily done because the sole-laying operator simply exercises the same care that he has always had to exercise in placing the toe and side edges of the shoe with extreme care in accurate alignment with the toe and side edges of the sole (except that he has heretofore exercised this care in placing the sole on the cavity, instead of as now the cavity on the sole), and this results in automatically getting the filler piece where it should be with relation to the cavity. In other words I simply provide a filler piece which can be placed readily and then I provide either in or on said filler piece just enough friction surface or adhesive to prevent the edgewise slipping or shifting of the piece

during the few moments until the shoe has been pressed down on the sole as stated. The sole layer then inverts the contacting shoe (with its last, etc.), sole and filler piece, and holds it to a nailing machine which nails the sole at the toe, shank and heel in usual manner, whereupon the last is removed and the shoe goes to the sole stitcher. When stitched, as shown at 30, Fig. 14, it is ready for the sole leveling operation, which is the final important step of my filling process. I have found that in practice this water film is sufficient for practical purposes as merely a temporary adhesion is really all that is needed at this point as permanent adhesion is secured by the squeezing out or spreading by the leveling pressure of the intermediate plastic filler layer of the filler piece into the shoe cavity beyond the boundary of the supporting layer or layers of said piece, which effectively sticks or unites the entire filler layer permanently to the inner sole and the outer sole. Mainly I am describing my invention in connection with McKay shoe manufacture, but this method of securing permanent adhesion is of special value in filling welt shoes. But for still greater efficiency I prefer to provide the supporting layer or layers themselves with an adhesive, preferably latent and brought into action by the immersion step. Also I preferably make the filler piece, as already explained, spreadable in whole or in part with sticky material or at least with cavity occupying material so that when once leveled the filler piece is thereby rendered permanently unchangeable or unshiftable in position. The immersion step of the process is preferably in hot water so as to condition the filler piece more rapidly as the laying of the filler piece occupies so much less time than the filling operation as heretofore practiced that it is advisable to have a large number of filling pieces being wetted. Nevertheless the filler piece itself is positioned really at normal working temperature. In other words the hot water is not for melting the binder and does not in fact affect the binder, unless, for instance, paste-forming ingredients have been used in the filler piece. In the latter case the marginal portions may be influenced slightly by the immersion step. It will be understood that I am broadly setting forth the main features of the new process and that I do not intend thereby to exclude from the same or from certain new steps therein the employment of other or additional means. For instance, in stating that a temporary adhesive only is required I do not thereby intend to exclude the employment of a permanent adhesive. So also, although I have emphasized the fact that the hot water treatment is not for the purpose of conditioning the filler itself, it will be understood that a filler piece could be employed which would be condi-

tioned by hot water treatment which in that case would be advantageous and within the purview and claims of this patent as to other steps and features. Such piece and its use would be in addition to certain other novel features of my invention. Such pre-treatment or conditioning and quickening per se is broadly claimed in my method application Serial No. 242,085 which is the generic method case as to employing quickening, and as to employing pressure, as to standard piece-application, as to employing latent adhesives (whether internal or external), as to employing a plastic piece, with or without skin or cover support or supports, and as to anti-squeak applications and manipulation. Such piece and its use when not restricted to the other novel features of the present case is broadly contained and claimed in my copending applications Serial No. 242,085 just mentioned, and Serial No. 228,588. The present application covers primarily a cold filler process and not primarily dependent on heat (excepting heat for quickening in connection with the cold process or with other steps of novelty of the process covered by the present application), whereas said application Serial No. 242,085 is the broad application covering generically the heat treatment process as such when applied to a piece and spreading the same. Said other last mentioned application covers broadly also any quickening process in connection with a filler piece as such, including the moisture quickening, hot or cold, of the piece as a piece of integral handleable layer for placing and spreading in a shoe-bottom. On the other hand, the use of hot water as above explained herein and so far as relates to the process of this application and the claims thereof is primarily simply for the wetting effect and the heat is simply to make it effective quicker by appreciably penetrating the paper or other cover more quickly than cold water would penetrate. The filler pieces are so constructed that they respond quicker to hot water than to cold water but it is simply the water or moisture that is relied upon and not the heat. The real laying of the filler is effected by the leveling process which comes at a considerable period later when all the heat has long since left the positioned piece in the shoe-bottom cavity. My filler piece is constructed to spread at normal temperature, and this spreading does in fact take place at such subsequent period, viz. the time of leveling pressure, that even though the filler had originally become softened by the heat of the water immersion it would long since have become cold again and the actual spreading or shoe-bottom filling operation would be effected cold or at normal working temperature. Reverting however to the contemplated more thorough conditioning of the filler material, as alluded to above, this is

either by water or other means of rendering the surface of the filler piece active, or, the filler material itself in the case of bulk filler, or the surface and appreciable penetration in the case of sheet filler not provided with a skin or supporting cover or layer. In such instances the water treatment is sufficiently thorough not only to supply the moisture film already explained, but it is relied upon to bring about such physical or chemical changes and conditions as the filler composition provides for, and to render more flexible and pliable the skin or supporting layer, if any. For instance, numerous slippery-producing compounds have been already set forth, and these can be rendered active or aided by the water treatment. And instead of water, oil or emulsion producing solutions may be used. One important feature in this line is in the case of a filler piece without a protective skin and made non-sticky and dormant by any of the means mentioned as by a coating of talc or other dormant element, in which case the required conditioning may be by painting the surface with paraffin oil. The conditioning brings about, in any case, a temporary activity by rendering the filler piece or material sticky, or slippery, pliable, more readily spreadable, and in general more responsive to the laying operation and the leveling, etc., and then the means employed therefor disappears largely or entirely, as by evaporation, absorption or conversion.

If the filler material be supplied to the shoe manufacturer in the form of string-like pieces of the kind shown in Fig. 7, or if it be cut into such pieces by the manufacturer, I find that one convenient method of procedure in applying these pieces to the shoe bottom consists in taking one of these strings of united filler pieces or leaves and throwing it over a convenient support, for example the shoulder of the operator, thus leaving both of the operator's hands free. The operator may now remove the endmost filler leaf or piece from the string by tearing, and attach it to the central part of the sole of the shoe with or without immersion treatment but preferably thoroughly wetted, as the latter is my preferred method or process as herein-after claimed. The wetting step may be supplemented by using a portion or all of the sticky layer surface. While it is usually sufficient to remove a small part of the web and thus to expose only a relatively small spot of sticky material, I contemplate that the web may be removed completely from one surface of the piece, if desired. Whether a spot or the whole surface be exposed, it is now, preferably after the wetting operation, laid as previously described, except that a little pressure, as by the thumb, is applied over the exposed spot or surface of sticky material against the shoe sole where it adheres firmly and with sufficient tenacity so

that there is no danger of displacement during the application of the rest of the shoe.

To facilitate removal of the skin or web from the piece, I may, if desired, touch the 5 filler leaf to a hot plate or other surface for an instant just sufficient to soften the sticky binder and thus free the skin or web so that it may be pulled off more readily. This application of heat is not intended to be sufficient to soften the body of the plastic filler 10 layer, but merely to soften the binder at the surface. While this softening of the binder just beneath the web facilitates removal of the web, it also makes the binder abnormally 15 sticky so that it adheres to the shoe bottom very easily.

While I may remove a portion or all of the web, as above described, after separation of the filler piece from the string or series, I 20 find that it is very convenient to remove this section of the web concomitantly with the separation of the filler piece from the string. This may be done, as indicated in Fig. 9, by subjecting the endmost piece L' to a slight 25 twist as it is torn off from the next adjacent package, such action having a tendency to pull the uniting skin away from the plastic layer for a short distance, although I find that usually the web or paper will begin to 30 tear, as indicated at C, Fig. 9, after a short portion has pulled off from the intermediate layer, thus exposing but a relatively small part 15^b of the plastic filler material to form the attaching means.

35 In the McKay construction the plastic filler material is spread by the pressure over the inner sole E and thence over the inner edges of the upper and fasteners F and the folds or plaits 26 upon the marginal portion of the inner sole. In a welt shoe this cavity is 40 defined by the inseam and is usually deeper than that in a McKay shoe. Whether the filler leaf be applied to a McKay or a welt shoe, my process renders it unnecessary to 45 make the same conform with any degree of exactitude to the shape of the cavity. It will be understood that the usual shank piece or stiffener is applied and the heel seat completed in any usual manner and at the usual 50 stage of operations. The outer sole 29 is secured to the shoe in any usual way, as by 55 stitches 30 indicated in Fig. 14, where a McKay shoe is illustrated. After the attachment of the outer sole, the shoe is subjected to the usual heavy pressure in a leveling machine, 60 which completes the shoe-bottom filling operation as the final step of my novel process. While undergoing this leveling pressure, the cold but plastic filler material 15 moves outwardly and then in whatever direction the 65 cavity and circumstances make possible, exuding from between the webs 11 and 14 and filling the shoe-bottom cavity as well as all crevices and spaces between the folds of the edge portion of the upper. The exuded ma-

terial 15^c (Fig. 15) forms a smooth and level surface which engages the inner side of the inner sole as well as of the outer sole and, as this exuded material is very sticky and adhesive it sticks also to the outer or marginal portions of the inner surface of the outer sole as well as to the edge portions of the upper, thus firmly uniting the outer sole to the upper and also to the inner sole so that the bottom of the shoe becomes practically a unit. 75 With this construction it is possible to employ a thinner inner sole than is usual, since the inner sole is virtually "plumped" by the filler layer and is reinforced by the outer sole while the outer sole finds a uniform support over its entire area and is thus less subject to wear than when it is irregularly or inadequately supported, as heretofore. In filling a welt shoe it may be desirable to apply the spreading pressure before the outer sole is applied, as set forth in my application Serial No. 242,085 where various features herein enumerated are still further explained and their advantages pointed out.

I have used the term "distensible" or "expandable" filler piece to define the broad generic structure of a filler piece so constructed and positioned that it is capable of lateral enlargement or expansion in the shoe cavity irrespective of whether it is plastic or not. 85 I have used the term "spreadable" filler piece or layer to define a plastic article which may be squashed or crushed and hence expanded in this way, i. e. by being moved one particle on another. A type of the expandable filler 90 piece which is not spreadable is described in the copending application Serial No. 212,747, filed August 13, 1927. A type of the expandable filler piece which is spreadable is described in my application Serial No. 133,506. 95

The adhesive binder is of a waterproof nature as well as constituting an anti-squeak element and as it is forced outwardly into the crevices between the outer sole and the in-turned edge of the upper, it forms a waterproof barrier which prevents the entrance of water between the soles. As this placing or positioning thereof is effected after the sole laying, it leaves the parts effectually waterproofed or given an anti-leak and an anti-squeak condition.

During the leveling operation the central portions of the webs or skins 11 and 14 of the filler piece approach each other due to the convexity of the inner sole so that the space between them becomes very small and in many cases is negligible. Thus, after the completion of the leveling operation, these substantially contacting webs form a barrier which prevents any subsequent movement of the plastic filler material so that there is little possibility of bunching of the material during wear. Although the filler piece (of the preferred laminated type) is necessarily put in place before the leveling operation, the

sticky substance thereof is not interposed between the marginal portion of the inner surface of the outer sole and the adjacent shoe parts until after the outer sole is stitched or 5 otherwise fastened in place, whereupon said sticky substance is interposed as stated, thereby waterproofing said surfaces and especially the edges, crimped upper and irregularities bounding the cavity 25. Concomitantly 10 with this spreading, the paper-like layers 11 and 14 are brought towards each other in the middle area into the space formerly occupied by the plastic filler which has just left or been pressed out. This constitutes a barrier, so positioned as to prevent any return movement of the extruded filler. In my application Serial No. 212,018, filed August 10, 1927, I have disclosed a method and article for filling the shoe bottom by applying the 15 filler piece marginally first and then pressing it or causing shifting inwardly toward the center instead of first applying the filler in the center and then shifting outward, and it will therefore be understood that, in its 20 broader aspects, the present patent is generic to both methods.

Under some circumstances, to facilitate the lateral spreading or expansion of the filler piece, I may form a slit or slits 64 (as 25 shown for example in the protector skin 24 in Fig. 10) in one or both of the skins 11 or 14, and when the slitted or incised piece is subjected to pressure, these slits widen and expose the plastic filler layer 15^a which was 30 previously held dormant or externally inactive but which now readily exudes through these slits and adheres to contiguous parts of the shoe and also constitutes an anti-squeak coating. In any event, my process forces 35 sufficient filler material throughout the bottom and bring the parts into such mutually supporting and retaining relation as to make the shoe bottom anti-squeak (as duly claimed in my method case Serial No. 242,085, filed 40 December 23, 1927). In the earlier part of 45 this specification I have set forth a filler piece in which an element is held dormant chemically to be set free later for causing external adherence of the piece, and in Fig. 50 10 as just explained I accomplish said result mechanically by holding the internal layer, as for example the sticky layer 15^a, dormant by means of the outer skin or skins, as 24 Fig. 10, until spread therefrom laterally and it may be therethrough, if slitted or 55 fragile or permeable or otherwise removable as a dormant-maintaining means.

I have already at the beginning of this patent summarized certain leading features of 60 novelty or steps and sequences of steps of my process, and I now enumerate these and others, but only in a general way, as I refer to the appended claims for a more complete enumeration and definition of my method and 65 its detailed steps. My process is broadly

novel, first, in using vertical pressure, preferably the leveling pressure for the final positioning of the filler layer; second, in providing a distensible or expansible filler piece or leaf that is automatically distended or expanded preferably by the leveling pressure; also in providing such capacity of expansion preferably in the form of a spreadable, i. e. squashable article (this feature, however, and the next herein enumerated being now transferred to and claimed broadly in my application Serial No. 242,085); and also preferably as a laminated piece; also in bringing into action in the shoe bottom the stickiness of the filler layer by pressure as distinguished from heat; also in using a colloidal element and changing the composition by heavy pressure; also in effecting the spreading cold or without heat treatment; also in effecting an increased inherent stiffening or resistance to subsequent shifting by applying heavy pressure to the filler layer; in accomplishing the last-enumerated step by the aid, in whole or in part, of included water; in providing absorbent and absorbed elements and manipulating them in the process; in providing a barrier to a binder element and removing it in the process; and in providing the automatic outlining of the ultimate filler layer, or, in other words, the automatic filling of the cavity, by the closing in approach of the inner sole and the outer sole towards each other; and, in making McKay shoes in beginning the filler laying on the outer sole; in doing this filling operation at the stage of the sole laying operation; in fastening the filler, as a piece, on the outer sole, preferably transiently; in completing the sole laying and sole fastening with the filling operation not yet completed and so as to hold the filler piece fixed for subsequent expansion; and finally in completing the filler laying operation or filler expansion step at the time of and by means of the sole leveling operation.

While I have described a certain order of steps as desirable in filling a shoe in accordance with my present process, it will be understood that my invention in many respects is otherwise usable or adaptable. For example, in adapting my process to the manufacture of welt shoes it is preferable to fasten the filler piece or pieces in the bottom cavity direct instead of on the outer sole. Hence, I wish it to be understood that the process is not necessarily limited to this particular order of steps and that certain of the steps may be omitted or that other steps may be substituted for those here specifically described without departing from the spirit of the invention as defined in certain of the following claims.

I claim:

1. That process of filling shoes which comprises placing in the bottom cavity of a shoe

- a quantity of plastic spreadable filler material of different contour and smaller area than the cavity, and subjecting said filler material to a single stroke of pressure applied 5 at the same time over the whole area of the cavity and solely in a direction substantially vertical to the shoe bottom to spread the filler material to the confines of the cavity.
2. That process of filling shoes which comprises depositing in the bottom cavity of a shoe a quantity of plastic spreadable filler material suitable for filling the cavity but of smaller area and greater thickness than the cavity, then placing a pressing surface 10 over the deposited filler and the cavity so as to enclose the cavity at and throughout its peripheral upstanding rim, and applying pressure through said pressing surface in a substantially vertical direction to spread the 15 filler to the confines of the closed cavity while said cavity is still closed against improper escape of the filler past said rim during the spreading of the filler.
3. That process of filling shoes, which comprises as steps providing an expansible filler piece, securing said piece in position on the inner face of the outer sole, assembling the rest of the shoe-bottom and said outer sole and filler piece in proper relation for fastening 20 the outer sole to the shoe-bottom, and then fastening said outer sole to the shoe-bottom with the filler piece against the cavity of the shoe-bottom, and spreading the filler piece by pressure.
4. That process of filling shoes, which comprises placing in a shoe-bottom cavity, a sheet-like piece of filler material having within it adhesive characteristics capable of becoming effectively sticky with relation to adjacent shoe-cavity surfaces by pressure as distinguished from heat, and then applying to said piece pressure to stick the filler thereby in place.
5. That process of filling shoes, which comprises placing in a shoe-bottom cavity filler material containing a dormant, stiffening ingredient adapted to be rendered active by pressure, and then applying pressure to said filler material sufficient to render said stiffening 45 ingredient active in the filler material.
6. That process of filling shoes, which comprises placing in a shoe-bottom cavity spreadable shoe filler material which contains an admixture of free liquid, as distinguished 50 from a solution of an ingredient of the filler material, adapted to be separated from the materials with which it is mixed by pressure, thereby to render the filler material stiffer and less liable to shift, and then applying pressure to said filler material sufficient to 55 separate said liquid and to effect said resistance to shifting tendency in the filler material.
7. That process of filling shoes, which comprises placing in the shoe bottom filler mate-
- rial containing an absorbent and an absorbed ingredient, and separating the same by pressure.
8. That process of filling shoes, which comprises placing in the shoe-bottom filler material containing an absorbent and an absorbed ingredient capable of evaporating when released, and releasing the same by pressure. 70
9. That process of filling shoes which comprises placing in the shoe-bottom filler material containing an absorbent and an absorbed ingredient capable when released of acting as a lubricant to facilitate the movement of the filler material to its final position in the shoe-bottom, and then releasing said ingredient by pressure and causing the same to act as a lubricant and facilitate the movement of said filler material to its said final position 75 in the shoe-bottom.
10. That process of filling shoes, which comprises placing in the shoe bottom filler material containing an absorbent and an absorbed ingredient containing water, and separating the same by pressure. 80
11. That process of filling shoes, which comprises placing in the shoe-bottom filler material which includes an absorbent containing an oily absorbed ingredient, and compressing the same sufficiently to release at least a part of the contained ingredient. 90
12. That process of filling shoes, which comprises placing in the shoe-bottom filler material containing an absorbent, an absorbed ingredient, and a compound capable of uniting with said absorbed ingredient when released, and then releasing said absorbed ingredient by pressure to unite with said compound. 100
13. That process of filling shoes which comprises placing in the shoe bottom filler material containing an absorbent, and absorbed ingredient, and a compound capable of uniting with said absorbed ingredient when released to act as a lubricant and then as a stiffener, and then releasing said absorbed ingredient by pressure to unite with said compound and effect said results. 105
14. That process of filling shoes, which comprises placing in the shoe-bottom filler material containing an absorbent, an absorbed ingredient, and a compound capable of uniting with said absorbed ingredient when released to act as a lubricant and then as a stiffener, and then releasing said absorbed ingredient by pressure to unite with said compound and effect said results, and thereafter permitting said released ingredient to produce further stiffness and compacting of the laid filler by subsequent absorption. 110
15. That process of filling shoes, which comprises providing as an article of manufacture a self-sustaining, shape-maintaining filler piece which is expansible, placing the same between the inner sole and outer sole in the shoe-bottom cavity, and then expand- 120
- 130

ing said piece within the confines of the cavity.

16. That process of filling shoes, which comprises providing filler material composed of at least three parts, viz. a body material and a binder, having a tendency to unite, and means constituting a barrier tending normally to restrain said union prior to use, placing said filler material in the shoe bottom while in said condition, and then releasing said barrier by pressure and causing said union.

17. That process of filling shoes, which comprises providing filler material composed of at least three parts, viz. a body material and a binder, having a tendency to unite, and means constituting a barrier tending normally to restrain said union prior to use, placing said filler material in the shoe-bottom while in said condition, and then by pressure releasing said barrier and causing said union.

18. That process of filling shoes, which comprises providing filler material composed of at least three parts, namely, a body material and a binder, having a tendency to unite, and means constituting a barrier tending normally to restrain said union prior to use and capable on release of constituting a flux for the filler material, placing said filler material in the shoe-bottom while in said condition, and then releasing said barrier by pressure and causing said union and using said barrier means to cause it to flux the filler and render it temporarily more movable.

19. That process of filling shoes, which comprises placing in the shoe a bottom filler in the form of a sheet like piece containing an inactive element capable of becoming externally active and rendering the filler material adherent to the adjacent parts of the shoe bottom, and then rendering said inactive element active to cause said adherence.

20. That process of filling shoes, which comprises placing in the shoe a bottom filler material containing an inactive element responsive to pressure to be made active thereby so as to render the filler material adherent to the adjacent parts of the shoe bottom, and then applying pressure to render said inactive element active to cause said adherence.

21. That process of filling shoes, which comprises applying a plastic and spreadable but coherent and self-supporting filler leaf to a shoe-bottom, said piece having an area less than the area of the cavity and a thickness greater than the depth of the cavity, and subjecting said leaf at normal temperature to pressure sufficient to cause it to spread to the increased area and reduced thickness required to conform to the shape and dimensions of the cavity.

22. That process of filling shoes, which comprises as steps sticking a coherent and shape retaining but plastic and spreadable layer of filler material to the inner sole, said piece having an area less than the area of the

cavity and a thickness greater than the depth of the cavity, and spreading said layer to the increased area and reduced thickness required to conform to the shape and dimensions of the cavity by the application of heavy pressure at normal temperature.

23. That process of filling shoes, which comprises applying to the shoe bottom a filler leaf comprising a spreadable layer of sticky plastic filler and reinforcing means making said leaf normally coherent and shape retaining, and subjecting said leaf to pressure while cold, thereby causing the plastic layer to spread relatively to its reinforcing means.

24. That process of filling shoes, which comprises applying to the bottom of a shoe a filler piece comprising a layer of sticky shoe filler material having an outer skin on at least one side, securing the outersole to the shoe, and applying pressure to said piece through the outersole sufficient to cause said sticky layer to spread beyond the edges of said skin.

25. That process of making shoes, which comprises as steps interposing a sticky substance between the central part of the outer sole and the inner sole of a shoe while excluding the central portion of the outer sole from contact with said substance, securing the outer sole to the shoe, and thereafter causing said sticky substance to spread outwardly toward the margin of the outer sole.

26. That process of filling shoes, which comprises as steps interposing between the inner sole and outer sole of the shoe a filler layer having a sticky moldable portion normally interposed between substantially non-adhesive skins, and subjecting the shoe to leveling pressure whereby to cause the moldable filler to exude and form a sticky edge around the skins.

27. That process of making shoes, which comprises as steps interposing a plastic substance between the inner sole and the central part of the outer sole of a shoe, and thereafter causing said plastic substance to flow outwardly toward the margin of the outer sole while concomitantly providing means tending to prevent subsequent movement of said plastic substance.

28. That process of making shoes, which comprises as steps interposing a plastic substance between the inner sole and the central part of the outer sole of a shoe, and thereafter causing said plastic substance to spread outwardly toward the margin of the outer sole while concomitantly positioning a barrier to prevent its return.

29. That process of making shoes, which comprises as steps interposing a plastic substance between the inner sole and the central part of the outer sole of a shoe, and thereafter causing said plastic substance to move outwardly toward the margin of the outer

- sole while concomitantly moving a non-plastic element into the space at the central part of the shoe formerly occupied by the outwardly moved plastic substance.
- 5 30. That process of making shoes, which comprises as steps interposing a plastic substance between the inner sole and the central part of the outer sole of a shoe, and thereafter causing said plastic substance to spread outwardly toward the margin of the outer sole while concomitantly moving a paper-like material into the space at the central part of the shoe formerly occupied by the outwardly spread plastic substance.
- 10 31. That process of making shoes, which comprises as steps providing a series of united sheet-like pieces each comprising a layer of sticky filler material and a protective skin, tearing off a piece from the end of the series 15 in such manner as at least partially to remove the skin from the separated piece, thereby exposing the sticky filler, and attaching the piece to the inner sole by means of the sticky filler so exposed.
- 20 32. That process of filling shoes, which comprises providing a shoe filler piece having a plastic sticky layer and a protective skin which is relatively non-adhesive, touching said piece to a hot surface to facilitate removal of a portion at least of said skin, removing at least a portion of the skin, and applying the exposed sticky layer to a shoe bottom.
- 25 33. That process of filling shoes, which comprises as steps providing a self-supporting filler piece consisting of a layer of plastic filler material combined with a layer of supporting material, the latter being provided with regions of weakness at some stage of its manufacture or use to reduce its resistance to lateral spreading, applying said filler piece to a shoe bottom, and subjecting said piece to pressure to cause it to expand laterally.
- 30 34. That process of filling shoes, which comprises as steps preparing a coherent sheet-like piece comprising a layer of plastic sticky filler interposed between paper-like skins, slitting one of said skins to weaken it, placing the piece in the cavity of a shoe bottom, and subjecting said piece to pressure such as to spread it laterally and cause the slits to widen and expose the filler layer.
- 35 35. That process of making shoes, which comprises as steps providing a filler piece having a layer of plastic sticky material interposed between relatively non-sticky outer skins, providing a sticky spot on one side of said piece, applying said sticky spot to an element of a shoe-bottom to attach the filler piece thereto, placing the outer sole and rest of the shoe-bottom together, and leveling the shoe-bottom.
- 40 36. That process of filling shoes, which comprises as steps stripping off a portion at least of the protective skin from a filler piece
- 45 comprising a layer of plastic sticky filler material and a protective skin, thereby exposing the sticky filler, attaching said piece to the bottom of a shoe by applying the exposed surface of the filler to one of the soles, and subjecting the filler piece to pressure to conform it to adjacent shoe parts.
- 50 37. That process of filling shoes, which includes as steps, providing filler material which comprises comminuted absorbent body material whose particles are enclosed with a removable barrier normally protecting said absorbent particles, and then removing said barrier from said previous protecting relation by pressure applied to the laid filler.
- 55 38. That process of filling shoes, which includes as steps, providing comminuted filler material whose particles are enclosed and protected by an external coating which is substantially permanent for purposes of handling and transportation and which then maintains the interior of said particles inaccessible to external influence, and then removing said coating as a protector by pressure in connection with the bottom filling operation.
- 60 39. That process of filling shoes, which comprises providing a self-sustaining, shape-maintaining filler piece which is expansible and is different in shape and smaller in area than the shoe-bottom cavity, placing the same between the inner sole and the outer sole in the shoe-bottom cavity, and then expanding said piece to the confines of the cavity.
- 65 40. That process of filling shoes, which comprises applying to the shoe bottom a filler leaf comprising a layer of sticky plastic filler and reinforcing means making the leaf normally self-sustaining and shape maintaining, and subjecting said leaf to pressure while cold to spread the plastic layer to the shape of the contiguous surfaces of the shoe bottom.
- 70 41. That process of making shoes, which comprises as steps providing a series of united sheet-like pieces each comprising a layer of sticky filler material and a protective skin, tearing off a piece from the end of the series in such manner as at least partially to remove the skin from the separated piece, thereby exposing the sticky filler, and attaching the piece to one of the surfaces forming the shoe-bottom cavity by means of the sticky filler so exposed.
